US00D615066S

(12) **United States Design Patent**
Huang et al.

(10) **Patent No.:** **US D615,066 S**
(45) **Date of Patent:** **** May 4, 2010**

(54) **PANEL PHONE**

(75) Inventors: **Chien-Ju Huang**, Taipei Hsien (TW);
Chi-Hsiang Kao, Taipei Hsien (TW);
Yi-Heng Hsu, Taipei Hsien (TW)

(73) Assignee: **Hon Hai Precision Industry Co., Ltd.**,
Tu-Cheng, Taipei Hsien (TW)

(**) Term: **14 Years**

(21) Appl. No.: **29/340,989**

(22) Filed: **Jul. 29, 2009**

(30) **Foreign Application Priority Data**

Apr. 3, 2009 (CN) 2009 3 0302170

(51) **LOC (9) Cl.** **14-03**

(52) **U.S. Cl.** **D14/142; D14/130**

(57) **CLAIM**

The ornamental design for a panel phone, as shown and described.

DESCRIPTION

FIG. 1 is a perspective view of a panel phone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of features on the rear of the panel phone in FIG. 3 is directed to environment and forms no part of the claimed design.

1 Claim, 7 Drawing Sheets
